UNITED STATES PATENT OFFICE.

EDWARD C. PARAMORE, OF PHILADELPHIA, PENNSYLVANIA, ASSIGNOR OF ONE-HALF TO HOWARD T. GOODWIN, OF RIDLEY PARK, PENNSYLVANIA.

COMBINED RELAY AND REPEATER FOR TELEPHONE-LINES.

SPECIFICATION forming part of Letters Patent No. 659,096, dated October 2, 1900.

Application filed November 18, 1899. Serial No. 737,482. (No model.)

To all whom it may concern:

Be it known that I, EDWARD C. PARAMORE, a citizen of the United States, residing at Philadelphia, (Germantown,) in the county of 5 Philadelphia and State of Pennsylvania, have invented new and useful Improvements in a Combined Relay and Repeater for Telephone-Lines, of which the following is a specification.

10 My present invention relates to combined relays and repeaters; and one object of the same is to provide a combined relay and repeater at the junction of two long-distance telephone-circuits which will receive voice-currents from either line and transmit them with increased volume or reinforced strength from the incoming line to the outgoing line with equal efficiency in either direction.

Another object is to provide a combined 20 relay and repeater which is automatically reciprocal in its action and which shall be so disposed that it will be fully responsive to currents originating in either circuit and will transmit said currents with increased volume 25 without reaction upon its own electromagnetic coils.

I attain the objects referred to by means of the construction shown in the accompanying drawings, in which—

30 Figure 1 is a diagram of two telephone-lines and showing my combined relay and repeater at the junction of said two lines. Fig. 2 is a side view of my combined relay and repeater. Fig. 3 is a vertical section through one of the 35 relay-transmitters. Fig. 4 is a face view of one of the transmitters, the diaphragm being removed. Fig. 5 is a plan view of the armature. Fig. 6 is a plan view of the diaphragm. Fig. 7 is a longitudinal section of the induction-coil.

Like characters of reference designate like parts in the different views.

Referring now to Fig. 2, the numeral 1 designates a suitable base or support. Secured to this base are four brackets 2, each comprising upright arms 3 and a right-angled foot 4, the latter being secured to the base 1. These brackets are arranged in pairs at the ends of the base, and secured to the upright 45 arms 3 of each pair of brackets is a relay-

transmitter 5. Since both of these transmitters are identical in construction and arrangement, a description of one only will be necessary for a full understanding of both.

Secured to the upright arms 3 of two of the 55 alined brackets 2 is a ring or annulus 6. The bolts or screws 7, four in number, hold the ring 6 firmly to said arms 3. A dome 8 is secured within the ring 6 by suitable means, such as a metallic strip or band 9, secured 60 centrally to the dome by a screw 10 and at the ends of the strip by the bolts 7.

The screw 10 passes into the dome and serves as a support for an electromagnet 11, the terminals from which pass through binding-tubes 12 12 at the bottom of the dome, and from thence one of said terminals is connected to one line-circuit and one to ground.

The ring 6 is rabbeted at 13, and within the recess thus formed the diaphragm 14 is 70 seated. A rubber gasket 15 covers the edge of the diaphragm, and said diaphragm is held in place by two or more turn-buttons or keepers 16, attached at their outer ends to the ring 6.

75 A slender spring 17, attached at the upper edge of the diaphragm, extends to the center of said diaphragm and is provided with a pointed electrode 18, which bears against the carbon button 19, secured to the end of a 80 spring 20, the upper end of which is secured to the adjusting-lever 21. This adjusting-lever is connected to a spring 22 at its upper end, said spring being attached to the ring 6 by screws 23. The lower end of the adjusting-lever is held in adjusted position by a set-screw 24, passing through a slot in the adjusting-lever and into a threaded aperture in the ring 6.

85 An induction-coil 25 is secured to the base 90 1 between the transmitters 5. This induction-coil 25 is supplied with three windings—two primaries 26, wound one on top of the other in order to bring them as close as possible to the magnetic core 25^a, and a secondary 95 32, wound on top of the two primaries. The extremes of the two primaries are connected up to wires 26^a and 26^b, respectively, which are connected in turn to the batteries 27 and the microphones on the repeaters 5. The 100

extremes of the secondary 32 are connected to wires 32^a, which are oppositely connected to the main-line wires, one through the binding-post *a* to the line *d* and the other through 5 the binding-post *a'* to the line *c*. The main lines, as shown, are grounded at both ends. When the transmitter on line *d* is being used, the vibrations are directly transmitted to the repeating-diaphragm 14. These are taken up 10 by the primary of the induction-coil and are intensified by the action of the battery 27 and induced in secondary 32 and transmitted to line *c* and thence to the receiver. As the apparatus is symmetrically arranged, the operation 15 of the other repeater is obviously the same as the one just described. It is true that the current will divide at *a* and a portion go directly into the secondary and thence over the line *c*; but since the resistance of 20 the secondary is relatively great as compared with coil 11 the interference caused by this division will be slight.

Having thus fully described my invention, what I claim is—

- 25 1. In a relay and repeater the combination of two telephone-lines, two repeating-magnets arranged to be actuated one by each of said telephone-lines, two microphones arranged to be actuated one by each of said repeating-magnets, an induction-coil, a first primary on 30 said induction-coil connected with one of said microphones, a second primary on said induction-coil connected to the other of said microphones, batteries in circuit with each of said primaries, and a secondary on said induction-coil, having each of its free ends connected

to one of said telephone-lines, substantially as described.

2. In a relay and repeater the combination of two telephone-circuits, two repeating-magnets one in each of the said telephone-circuits, two microphones, each being arranged to be actuated by one of said repeating-magnets, an induction-coil, a first primary on said induction-coil connected in circuit with one of 40 said microphones, a second primary connected in circuit with the other of said microphones, and a secondary on said induction-coil, which is wound on top of the two primaries and oppositely connected to each of 45 the said telephone-lines, substantially as described.

3. In a relay and repeater the combination of two telephone-lines, two repeaters one in each telephone-line, an induction-coil, a first 55 primary on said induction-coil, which is connected to one of said repeaters, a second primary on said induction-coil, which is connected to the other of said repeaters, a secondary on said induction-coil, which is connected at 60 one end to one of said telephone-lines and at the other end to the other of said telephone-lines, and batteries in circuit with said primaries, substantially as described.

In testimony whereof I have hereunto set 65 my hand in presence of two subscribing witnesses.

EDWARD C. PARAMORE.
